United States Patent [19]

Hiroki

[11] Patent Number: Des. 313,990

[45] Date of Patent: ** Jan. 22, 1991

[54] FACSIMILE TRANSCEIVER

[75] Inventor: Shin-ichi Hiroki, Tokyo, Japan

[73] Assignee: Kabushiki Kaisha Toshiba, Kawasaki, Japan

[**] Term: 14 Years

[21] Appl. No.: 383,579

[22] Filed: Jul. 24, 1989

[30] Foreign Application Priority Data

Feb. 27, 1989 [JP] Japan 6625/89

[52] U.S. Cl. D14/118

[58] Field of Search D14/118, 299; D18/36, D18/37; 358/400, 401
